UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

AUTOMATIC FILLING-REPLENISHING LOOM.

1,351,188.

Specification of Letters Patent. Patented Aug. 31, 1920.

Application filed November 20, 1919. Serial No. 339,330.

To all whom it may concern:

Be it known that I, ALONZO E. RHOADES, a citizen of the United States, residing at Hopedale, county of Worcester, State of Massachusetts, have invented an Improvement in Automatic Filling-Replenishing Looms, of which the following description, in connection with the accompanying drawings, is a specification, like characters on the drawings representing like parts.

This invention relates to automatic filling replenishing looms wherein a magazine or hopper containing a supply of fresh filling carriers is provided and wherein upon the call for filling replenishment a fresh filling carrier is transferred from this magazine or hopper to the lay. It sometimes happens that the supply of filling carriers in the magazine or hopper is allowed to run out. If this happens, or if for any other reason a fresh filling carrier is not in position in the hopper ready for transfer upon the call for filling replenishment, it follows that when the call for replenishment occurs the mechanism will go through the operations of transfer but without transferring any fresh filling carrier from the hopper to the lay with the result that one or more picks of imperfect weaving will occur before the loom is stopped.

It is the object of the present invention to provide a construction in which if, after a fresh filling carrier has been transferred from the hopper to the lay, the supply of fresh filling carriers has become exhausted or for any other reason a fresh filling carrier is not brought into position ready for transfer that the loom shall then be stopped, thus enabling the operative to fill up the hopper or properly position the filling carriers therein so that a fresh filling carrier will be in position for the next transfer.

It is the object of the present invention in the preferred form illustrated to provide a construction in which this stopping of the loom is effected through the agency of the usual warp stop motion employed on such looms.

These and other objects of the invention will appear more fully from the accompanying description and drawings and will be particularly pointed out in the claims.

The drawings show a preferred form of the invention embodied in an automatic

filling replenishing loom of the well known Northrop type.

In the drawings—

Figure 1 is a view in transverse section of a portion of the loom with a preferred form of the invention embodied therein.

Fig. 2 is a plan view partially in horizontal cross section of a detail showing the feeler for contacting with the filling carrier in the hopper and the immediate connections therewith.

Fig. 3 is a side view of a portion of the hopper showing the feeler arranged to detect at a different point from that shown in Fig. 1.

As the general construction and operation of the Northrop type of automatic filling replenishing loom is well known to those skilled in the art it will be necessary to describe only those features particularly related to the present invention.

In this loom the loom side 1 supports the usual crank shaft 2 by which the lay 3 is swung forward and back and the usual cam shaft 4. At one side of the loom is mounted the hopper stand 5 carrying the supply of fresh filling carriers 6, which in this type of loom are separately supported in a rotary feeder by which they are successively brought to transferring position, which is the position indicated as occupied by the filling carrier 6 in Fig. 1. When the running filling carrier has become wholly or partially exhausted suitable indicating means sets in motion mechanism by which replenishment is effected by a transfer of a fresh filling carrier from the hopper to the lay, and by which the exhausted filling carrier is forced out through the lay. This transfer is usually effected by a transference 7 pivoted at 8 which upon the call for filling replenishment swings downwardly forcing the filling carrier 6 out of the hopper on the lay which is then located directly beneath.

It will be recognized that if a fresh filling carrier is not located beneath the transference or in the position for transfer that the transferring mechanism will go through its motions without effecting any transfer, and the loom will continue to run with the exhausted filling carrier thus making one or more picks of imperfect cloth which it is highly desirable to avoid especially in the

automatic filling replenishment loom provided with a feeler for detecting substantial exhaustion of filling in the running shuttle and effecting transfer before complete exhaustion takes place.

This difficulty is obviated by the present invention by means of a mechanism which stops the operation of the loom if the supply of filling carriers has become exhausted, 10 or if a fresh filling carrier is not in position for transfer in the hopper, and in the preferred form illustrated this is effected through the usual warp stop motion.

A warp stop motion of a familiar type is 15 illustrated. In this type banks of drop wires 9 are provided, each drop wire being supported by a warp. If a warp breaks this drop wire falls and is caught between a box plate 10 and a feeler bar 11 constantly vibrated from the cam shaft 4. This locks the feeler bar 11 against vibration and effects a movement of the knock off link 12 thus rocking the lever 13 to throw the shipper handle 14 out of its retaining notch and allow it to spring to the end of its slot and disconnect the driving power thus stopping the loom all in a familiar and well known manner.

In the present invention a feeler 15 shown 30 as a flat metal finger is mounted on a stud 16 journaled in a bushing 17 threaded into the hopper stand 5, and so positioned that the curved end of the feeler rests against the butt of the filling carrier 6 when it is 35 in position in the hopper ready for transfer. The stud 16 at its opposite end has locked thereto by a set screw 18 a collar 19 provided with an upstanding arm 20 connected by a link 21 which runs rearwardly back to 40 and is connected to a bell crank lever 22 mounted adjacent the banks of the drop wires of the warp stop motion. The other arm of the bell crank lever 22 has pivotally suspended therefrom an auxiliary drop wire 23 which is positioned at the end of one of 45 the banks of drop wires. A light spring 24 coiled about the link 21 and abutting at one end a shoulder 25 on the loom arch 26, and at the other end a collar 27 on the link tends 50 to move the link rearwardly.

The operation will now be apparent. So long as a filling carrier 6 is in place in the hopper in position for transfer, the feeler 15 is held in its normal elevated position 55 with the parts in the position shown in Fig. 1 and with the auxiliary drop wire 23 elevated. If replenishment takes place and another fresh filling carrier comes into position for transfer the parts are retained in 60 this position and nothing happens. If, however, transfer takes place and the supply of fresh filling carriers in the hopper has become exhausted or if for any other reason no fresh filling carrier comes into position

for transfer there is nothing to support the 65 feeler 15 and it consequently through the action of gravity or aided by the spring 24 falls or swings downwardly about its pivot. This results in moving the link 21 rearwardly, in rocking the bell crank 22, and allowing the auxiliary drop wire 23 to drop between the box plate 10 and the vibrating feeler bar 11. This is the same action as the falling of a drop wire and consequently the loom is immediately stopped through 75 the action of the warp stop motion. The operative then replenishes the hopper or places a fresh filling carrier in position on the hopper ready for transfer and consequently no operation of the transferring 80 mechanism can take place without a fresh filling carrier actually being transferred.

In the construction illustrated in Fig. 1 the feeler is shown as positioned to indicate the absence of a fresh filling carrier 85 from transferring position, but it is obvious that this is but one of the predetermined positions, which the feeler may occupy. Its broad function is in detecting a predetermined degree of depletion of the supply of 90 fresh filling carriers in the hopper or in detecting the absence of a fresh filling carrier 95 at a predetermined point in the hopper. In Fig. 3 the feeler 28 is shown as arranged to detect the absence of the fresh filling carrier 100 at a different point as for example the third one away from transferring position.

Having thus described my invention what I claim as new and desire to secure by Letters Patent is—

1. An automatic filling replenishing loom comprising a rotary hopper containing a supply of separately supported fresh filling carriers, means for detecting absence of a fresh filling carrier from the hopper at 105 a predetermined point in its rotation, and mechanical means controlled by the detecting action of the detecting means to effect the stopping of the loom.

2. An automatic filling replenishing loom 110 comprising a rotary hopper containing a supply of separately supported fresh filling carriers, means for detecting absence of a fresh filling carrier from position ready for transfer upon the call for filling replenishment, and mechanical means controlled by the detecting action of the detecting means to effect the stopping of the loom.

3. An automatic filling replenishing loom 115 comprising a hopper containing a supply of fresh filling carriers for successive transfer to the lay, means for detecting a predetermined depletion of said supply, loom stopping means, a warp stop motion including a plurality of drop wires each movable into position to effect the actuation of the loom stopping means, and means controlled by the detecting action of the detect-

ing means to move one of the drop wires into position to effect the actuation of the loom stopping means.

4. An automatic filling replenishing loom comprising a hopper containing a supply of fresh filling carriers for successive transfer to the lay, means for detecting absence of a fresh filling carrier from transferring position, loom stopping means, a warp stop motion including a plurality of drop wires each movable into position to effect the actuation of the loom stopping means, and means controlled by the detecting action of the detecting means to move one of the drop wires into position to effect the actuation of the loom stopping means.

5. An automatic filling replenishing loom comprising a hopper containing a supply of fresh filling carriers for successive transfer to the lay, means for detecting the failure of the hopper to present a fresh filling carrier in position for transfer, loom stopping means, a warp stop motion including a plurality of drop wires each movable

into position to effect the actuation of the loom stopping means, and means controlled by the detecting action of the detecting means to move one of the drop wires into position to effect the actuation of the loom stopping means.

6. An automatic filling replenishing loom comprising a rotary hopper containing a supply of separately supported fresh filling carriers for successive transfer to the lay, a movable feeler held against movement by a filling carrier in position in the hopper for transfer to the lay, loom stopping means, and mechanical connections thereto for effecting the actuation of the loom stopping means by or through the movement of the feeler whereby absence of a fresh filling carrier from position in the hopper for transfer effects the stopping of the loom.

In testimony whereof, I have signed my name to this specification.

ALONZO E. RHOADES.
